UNITED STATES PATENT OFFICE

96,051

DESIGN FOR A COMBINED FLASH LIGHT AND UMBRELLA HANDLE OR SIMILAR ARTICLE

Samuel Osterman, New York, N. Y., assignor to Guth, Stern & Co. Inc.

Application April 13, 1935, Serial No. 56,365

Term of patent 7 years

To all whom it may concern:

Be it known that Samuel Osterman, a citizen of the United States, and resident of New York city, in the county of Kings and State of New York, has invented a new, original, and ornamental Design for a Combined Flash Light and Umbrella Handle or Similar Article, of which the following is a specification, reference being had to the accompanying drawing, forming part thereof, in which Figure 1 is a perspective view of a combined flash light and umbrella handle showing my new design, and Figure 2 is a bottom plan view thereof.

I claim:

The ornamental design for a combined flash light and umbrella handle or similar article, as shown.

Dated April 12, 1935.

SAMUEL OSTERMAN.
